UNITED STATES PATENT OFFICE.

JACOBUS FRANCISCUS GERARDUS JONGEPIER, OF SCHIEDAM, NETHERLANDS.

OFFICE-LEDGER.

1,355,903.

Specification of Letters Patent. Patented Oct. 19, 1920.

Application filed December 30, 1919. Serial No. 348,379.

To all whom it may concern:

Be it known that I, JACOBUS FRANCISCUS GERARDUS JONGEPIER, merchant, a subject of the Queen of the Netherlands, residing at 5 Schiedam, the Netherlands, 43 Lange Haven, have invented certain new and useful Improvements in Office-Ledgers, of which the following is a specification.

This invention has reference to ledgers 10 and the like and it has relation to ledgers and the like whose covers are provided on one or more of their edges with indicators or column markers that comprise strips divided in accordance with the columnar 15 ruling and bearing indications of the purpose of the ruling.

In such ledgers and the like the indicators or column markers have been mounted on the covers so that they can be folded within 20 the book; it is found that such indicators or column markers wear out rapidly and break at the hinge; they also suffer from the disadvantage that they cannot be placed in or out of use without it being necessary 25 to open the cover or turn over the pages.

The present invention overcomes the objections that pertain to the known construction and in accordance therewith an indicator or column marker (or indicators or 30 column markers) is mounted on the cover so as to be capable of sliding movement in relation thereto.

The accompanying drawing is partly a plan view, a part being broken away, of the 35 cover of a ledger.

The indicator or column marker 1 has a portion 2 that is divided in accordance with the columnar ruling of the pages of the book. The indicator or column marker 1 40 is in one piece with a part 3 having extensions or lugs 4 (only one is shown). The inside of the cover 5 of the book is provided with a pocket 6 and within the pocket 6 with blocks 7 (only one is shown). The parts 3 45 and 4 of the indicator or column marker are always contained within the pocket 6 and the indicator or column marker as a whole can be slid in and out thereof, the outward movement being limited by contact of the 50 extensions 4 with the blocks 7. 8 is a tab by which the indicator or column marker can be moved inward or outward of the pocket 6. The indicator or column marker can 55 also be moved inward of the pocket 6 when

the book is open by pressure on the part 55 that extends beyond the pages of the book. The tab 8 instead of being placed in the position in which it is shown may be attached to the indicator or column marker so that it protrudes even when the book is 60 closed and the indicator or column marker is in its inward position.

If desired, a number, letter or other sign may be placed on the indicator or column marker at the top of each division, as also 65 at the top of the corresponding column of the page.

Having fully described my invention, what I claim as new and desire to secure by Letters Patent is:—

1. In combination with a ledger, a column marker slidable on the inside of the cover of the ledger so as to be extended above the upper edges of the cover to coact with the ledger, and coactive means on the inside of 70 the cover and on the marker for limiting the sliding movement thereof.

2. In combination with a ledger, a marker slidable on the inside of the cover of the ledger and provided with a columnar ruling 80 longitudinally of the front face near the upper edge thereof and coacting with the leaves of the ledger when the marker is extended above the upper edges of the cover, and coactive means on the inside of the 85 cover and on the marker for limiting the inward and outward sliding movement thereof.

3. In combination with a ledger, blocks secured to the inside cover of the ledger at 90 the side edges thereof, a columnar marker slidable on the inside of the cover and lateral lugs at the opposite sides of the marker for coacting with the blocks for limiting the outward sliding movement of 95 the marker.

4. In combination with a ledger, a pocket on the inside of the cover of the ledger, opposed blocks secured to the inside of the cover near the side edges thereof, a column 100 marker slidable inside of the pocket and retained by the pocket, and lateral lugs on the opposite sides of the marker for coacting with the blocks so as to limit the outward sliding movement of the marker.

In testimony whereof I affix my signature.

JACOBUS FRANCISCUS GERARDUS JONGEPIER.
